DESIGN FOR A GRINDER FRAME

Ely Bockshe, Milwaukee, Wis.

Application June 21, 1933, Serial No. 48,490

Term of patent 14 years

To all whom it may concern:

Be it known that I, ELY BOCKSHE, a citizen of the United States, of Milwaukee, in the county of Milwaukee and State of Wisconsin, have invented a new, original, and ornamental Design for a Grinder Frame, of which the following is a specification, reference being had to the accompanying drawing, forming part thereof.

Figure 1 is a rear elevation of the grinder frame showing my new design.

Figure 2 is a side elevation of the same, and Figure 3 is a front elevation of the same.

I claim:

The ornamental design for a grinder frame, as shown.

In testimony that I claim the foregoing I have hereunto set my hand at Milwaukee, in the county of Milwaukee and State of Wisconsin.

ELY BOCKSHE.
